C. W. SHAEFFER

RUBBER HEEL

Filed April 29, 1921

INVENTOR.
CLARENCE W. SHAEFFER.

BY *Henry Blech*

ATTORNEY.

UNITED STATES PATENT OFFICE.

CLARENCE W. SHAFFER, OF CHICAGO, ILLINOIS.

RUBBER HEEL.

Application filed April 29, 1921. Serial No. 465,430.

To all whom it may concern:

Be it known that I, CLARENCE W. SHAFFER, a citizen of the United States, residing at Chicago, in the county of Cook and 5 State of Illinois, have invented a new and useful Improvement in Rubber Heels, of which the following is a specification.

The invention relates to improvements in rubber heels, and more particularly to pneumatic rubber heels.

It is an object of the invention to provide a rubber heel which is of simple construction, exceedingly efficient in use and capable of adhering to the surface on which it rests 15 so as to prevent slipping especially in moist weather.

A further object aims at providing a rubber heel, in which the suction effect is obtained by coring out the bottom deep enough 20 to simulate the action of a suction cap, so that strong adherence of the heel to a surface is insured.

Another object constitutes the provision of an air chamber in the heel for the purpose of increasing the resiliency thereof.

A still further object aims at providing the air chamber and the suction chamber in such coacting relation that the two chambers contribute to effect a practical satisfactorily acting resilient rubber heel, which 30 by virtue of such actions has a long life, and no diminution in effectiveness during use.

It is also an object to provide a tread surface which is of less area than the bottom of the heel, and which tread surrounds the suction chamber, and is subjacent to air chamber, so that upon impact of the tread surface on the ground the suction chamber 40 and the air chamber are called into operation, the former to cause adherence of the heel to the ground, the latter to absorb the impact and thus reduce the wear of the tread surface.

With these and other objects in view which will appear as the description proceeds, the invention, then consists in the novel construction of a rubber heel, as described in the specification, particularly 50 pointed out in the claims and illustrated in the accompanying drawing, in which—

Fig. 1 is an illustration of a shoe to which the invention has been applied.

Fig. 2 is a bottom plan view of the improved heel.

Fig. 3 is a top plan view.

Fig. 4 is a section on line 4—4 of Fig. 3.

Fig. 5 is a section on line 5—5 of Fig. 3.

Fig. 6 is a section through a modification.

Referring to the drawing, 10 designates a 60 shoe having the improved heel 11 secured thereto in any approved or preferred manner. The heel is constructed to provide a suction cup at the bottom, and an air chamber at the top, said chambers being in such 65 relative arrangement that both coact to meet the most stringent requirements as to durability, resiliency and lack of slipping upon wet ground. To this end the bottom face 12 is formed with a bead 13 substantially 70 equidistant from the perimeter of the bottom face, so that the bead constitutes the tread surface of the heel. The bead 13 surrounds a cored out portion 14 in the heel, which cavity is of considerable depth and 75 constitutes a suction chamber to cause adherence between the heel and the ground. The fact of providing a tread in the form of a bead enclosing a suction chamber insures 80 positive suction action and good adherence between the heel and the ground.

The top surface 15 of the heel has a slanting portion 16 from the perimeter to a bead 17, which is closer to the perimeter than the tread surface 13. The bead 17 is equidistant 85 from the perimeter and surrounds a chamber 18 which serves as an air spring to absorb shocks and jolts. The bottom of the chamber is convex as appears in the sectional views, and this form is caused by the concavity of the suction chamber bottom.

Attention is called to the fact that the tread surface 13 is subjacent the air chamber 18, and underneath a deep portion thereof, so that impacts and jars are effectively 90 and resiliently absorbed.

The heel is provided with the bead 17 to effectively lock the air in the chamber 18 whereby the air spring constituted by said chamber remains practically unaltered during the entire use of the heel. The slanting portion 16 furthermore establishes a suction engagement between the top surface of the heel and the shoe lift to which it is applied. The heel is equipped with the usual perforations 20, extending approximately half way through the heel for the insertion of nails to securely attach the heel to the shoe.

From the foregoing it follows that my improved rubber heels admirably meet all re- 110

quirements as to longevity, perfection in wear, resiliency and ability to prevent slipping.

If desired the bead 13 may coalesce in a slanting portion 21 shown in the modified Figure 6. This will also provide a tread surface less than the bottom area of the heel, and will establish an even wear of the tread surface in continuous and extended use.

While the drawing shows several preferred embodiments of the invention various changes, alterations and departures can be applied as will be readily seen by those versed in this art. It is, therefore, not my intention of confining myself to the exact details of construction as shown, but to avail myself of such changes and modifications which fairly fall within the purview of the invention as defined by the appended claims:

I claim:

1. A heel for shoes comprising a resilient

member, a suction chamber in said member having a deep portion and open at the bottom thereof, said chamber having a convex top, a bead surrounding the mouth of said chamber, and an air chamber above said suction chamber and spaced therefrom, said air chamber having a concave bottom to correspond to the convex top of said suction chamber and extending beyond the heel portion equipped with said bead.

2. A heel for shoes comprising a resilient member, an air chamber in said member and open at the top, a suction chamber in said member and open at the bottom, said suction chamber and said air chamber being separated by a concave-convex partition wall, and a protruding tread portion surrounding the mouth of said suction chamber and underlying a deep portion of said air chamber.

In witness whereof I affix my signature.

CLARENCE W. SHAEFFER.
